UNITED STATES PATENT OFFICE

ARTHUR L. SWANK, OF DETROIT, MICHIGAN, ASSIGNOR TO LONG MANUFACTURING COMPANY, OF DETROIT, MICHIGAN, A CORPORATION OF MICHIGAN

RADIATOR

Application filed December 22, 1924. Serial No. 757,535.

The invention relates to radiators and refers more particularly to radiator constructions used in connection with motor vehicles.

One of the objects of the invention resides in providing means for preventing the escape of the water from the radiator. In the radiator constructions heretofore, the water in the radiator frequently is raised to a temperature sufficiently high to cause vaporization or steam. Such steam is free to escape past the radiator filling cap or by way of the overflow pipe which affords a ready escape for such steam in the usual constructions of radiators in present use. The escape of the steam is objectionable in that the water supply in the radiator cooling system is diminished, requiring frequent replenishment. The appearance of the escaping steam is also undesirable. The present invention affords a simple construction, readily applied to the present radiator construction whereby the escape of steam from the radiator is prevented, at the same time preventing the building up of objectionably high pressures within the radiator. A further feature of the invention resides in providing means for retaining the overflow tube in position.

With these and other objects in view, the invention resides in the novel features of construction and combination and arrangements of parts as more fully hereinafter described and claimed.

Referring to the drawings:—

Figure 1 represents a fragmentary section of the upper portion of a radiator showing my invention applied thereto;

Figure 2 is an elevation of the baffle tube and overflow retainer; and

Figure 3 is a plan view thereof.

In the drawings reference character 10 indicates the radiator core, 11 the upper tank, 12 the filler connected therewith, 13 the radiator filler cap and 14 the casing, all of which parts may be of usual construction.

Extending upwardly through the tube sheet 15 is the overflow tube 16, open at its upper end adjacent the upper part of the filler 12 and above the normal water level indicated at $x-x$.

Concentrically with the filler 12 is the

baffle tube and overflow retainer 17 preferably formed of a metal stamping with the inwardly bent longitudinally extending portion 18 for receiving the overflow tube 16. The tube 17 is preferably formed cylindrically and of a diameter slightly greater than the inside diameter of the filler 12 to resiliently engage the latter and has its ends unconnected to provide a longitudinally extending slit 19.

For readily locating the tube 17 in position it is preferably formed with outwardly pressed ears 20 adapted to engage the lower end of the filler 12 and in such position the tube 17 may be soldered or welded in one or more spots to prevent relative movement of these parts.

In assembling the parts, the tube 17 is slightly contracted, by reason of the slit 19 and placed in the filler, the portion 18 receiving the overflow tube 16, until the ears 20 engage the lower end of the filler at which time the tube 17 is allowed to slightly expand to resiliently engage the filler and afford a small opening longitudinally of the cylinder by reason of the slit 19. In this position, with the lower end of the cylinder extending below the water line $x-x$, the cylinder may be spot welded or soldered in place, although the inherent resilience of the cylinder will normally prevent displacement of the tube.

It will be noted that the overflow tube 16 is securely located against movement at one side of the filler, being held between the latter and the tube 17. Furthermore, the tube 17 acts as a baffle substantially preventing steam collected in the tank 11 from escaping by way of the filler or overflow tube. Should there be a tendency to build up high pressures within the tank 11 it will be noted that the slit 19, while not permitting escape of steam to any appreciable extent, will nevertheless provide a ready check against building up of such pressures within the tank.

While it is believed that from the foregoing description, the nature and advantage of my invention will be readily understood, I desire to have it understood that I do not limit myself to what is herein shown and described and that such changes may be resorted to when desired as fall within the scope of the claims.

What I claim as my invention is:—

1. The combination with a radiator having a filler overflow tube and tank, of a tube insertable within the filler and extending below the normal water level of the tank for substantially preventing escape of steam from said tank, said tube provided with a slit affording relief for excessive pressure in said tank and with a groove for positioning said overflow tube.
- 10 2. The combination with a radiator having a filler, a tank and an overflow tube communicating with said filler, of a tube cylindrically formed and provided with a slit affording resilient engagement with the filler and escape of excessive pressure from said tank, said tube also provided with an inwardly bent portion serving to receive and position the overflow tube.
- 15 3. The combination with a radiator having a filler, a tank and an overflow tube communicating with said filler, of a tube cylindrically formed and provided with a slit affording resilient engagement with the filler and escape of excessive pressure from said tank, said tube also provided with an inwardly bent portion serving to receive and position the overflow tube, said tube also provided with outwardly pressed ears serving to engage the 20 lower end of the filler for positioning the tube therewithin.
- 25 4. The combination with a radiator having a filler, a tank, and an overflow tube, of a tubular member insertable within the filler and extending below the normal water level for the tank for substantially preventing escape of steam from said tank, said tubular member being provided with means above the water level for affording relief of excessive pressure from the tank, and with an offset portion for receiving and positioning the overflow tube.
- 30 5. The combination with a radiator having a filler, a tank and an overflow tube, of a tubular member provided with a slit affording resilient engagement with the filler and escape of excessive pressure from said tank, said tubular member being also provided with an offset portion serving to receive and position the overflow tube.
- 35 6. The combination with a radiator having a filler, a tank and an overflow tube, of a tubular member insertable within the filler and extending below the normal water level of the tank for substantially preventing escape of steam from said tank, said tubular member being provided in the wall thereof with a passageway for affording relief of excessive pressure from the tank, and with an offset portion for receiving and positioning the overflow tube.
- 40 7. The combination with a radiator having a filler, a tank and an overflow tube, of a tubular member insertable within the filler and extending below the normal water level of the

tank for substantially preventing escape of steam from said tank, said tubular member being provided with means extending above the normal water level of the tank for affording relief of excessive pressure from the tank, and with an offset portion for receiving and positioning the overflow tube.

In testimony whereof I affix my signature.

ARTHUR L. SWANK.
